UNITED STATES PATENT OFFICE.

ABE ROBINSON, OF BROOKLYN, NEW YORK.

CLOCK-WINDING MECHANISM.

SPECIFICATION forming part of Letters Patent No. 366,429, dated July 12, 1887.

Application filed June 2, 1886. Serial No. 203,920. (Model.)

To all whom it may concern:

Be it known that I, ABE ROBINSON, of Brooklyn, in the county of Kings and State of New York, have invented a new and Improved 5 Clock-Winding Mechanism, of which the following is a full, clear, and exact description.

The object of my invention is to provide a new and improved automatic winding mechanism for clocks actuated by springs.

10 The invention consists of a wind-wheel actuating a train of gear-wheels connected with the spring-barrel of the clock mechanism, and of an automatic wind-wheel-locking device.

15 The invention also consists of various parts and details and combinations of the same, as will be fully described hereinafter, and then pointed out in the claims.

20 Reference is to be had to the accompanying drawings, forming a part of this specification, in which similar letters of reference indicate corresponding parts in all the figures.

25 Figure 1 is an elevation of my improvement, parts being in section. Fig. 2 is a bottom view of the same. Fig. 3 is a rear view of the locking device in its locked position. Fig. 4 is a similar view of the same in an unlocked position. Fig. 5 is a cross section of the same on the line xx of Fig. 4. Fig. 6 is a face view of the transmitting-wheel of the locking device. 30 Fig. 7 is a similar view of the same from the other side. Fig. 8 is a central section on the line yy of Fig. 2. Fig. 9 is an inner face view of the transmitting-wheel for the striking mechanism, and Fig. 10 is an enlarged detail plan view of the locking device.

35 A wind-wheel, A, of any approved construction, is mounted in a frame, B, attached to the casing C, in which is mounted, in a suitable frame, D, an ordinary clock mechanism actuated by a coil-spring, one end of which is attached to the barrel E, the other end being attached to the spindle F, which forms a bearing for the barrel E, which operates the clock mechanism in the usual manner.

40 45 The casing C is preferably made in two parts, separated by a partition, C', so as to establish a flue, C'', from which the air or draft passes through the wind-wheel A and rotates the same, and then the air passes into the flue or shaft connected with the rear end of the frame B of the wind-wheel A.

50 The wind-wheel A is mounted on a shaft,

A', which has its bearing on the casing B and the partition C', passing through the latter and being provided on its inner end with a crank-arm, G, which connects loosely with the arm H, attached to the spindle I, having its bearing on the swinging frame J, pivoted on a stud, J', attached to the plate J'', mounted on the frame D, carrying the clock mechanism. 55

On the spindle I is secured a pinion, I', which meshes into the gear-wheel I'', attached to a spindle, I'', having its bearing in the swinging frame J, and the spindle I''' is provided with the pinion I''', which can be thrown in and out of gear with the gear-wheel K, which is one of a train of gear-wheels connected with the gear-wheel L, mounted on the spindle F, which forms a bearing for and is connected with the spring-barrel E. The gear-wheel L 70 meshes into the gear-wheel M, secured to the spindle M', which carries loosely the gear-wheel M'', operating the striking mechanism of the clock in the usual manner. To the gear-wheel M'' is attached one end of a spring, M''', 75 one end of which is secured to the ratchet-wheel M'', also placed loosely on the spindle M' and engaging a pawl, M''', mounted on the frame D, carrying the clock mechanism. The ratchet-wheel M'''' is fastened to the spindle M' 80 and engages a spring-pawl, M''', pivoted on the ratchet-wheel M''.

On the gear-wheel L is mounted a transverse spindle, N, which carries on one end one face of the wheel L, a cam, N', and the other end, on the other face of the wheel L, carries a segmental gear-wheel, N'', which engages with a stud, E', attached to the spring-barrel E, so that for every revolution of the wheel L the segmental gear-wheel N'' is turned 90 the distance of one tooth and the cam N' is turned the same distance.

On the cam N rests the collar O, placed loosely on the spindle F, which collar is raised or lowered by the action of the turning of the cam N'. On the collar O rests the free end of the spring O', secured to the plate J'', and the free end of the spring is provided with the bent arm or plate O'', which projects through the plate J'', and is provided with the inclined slot O''', through which passes, on the outer face of the plate J'', the lever P, pivoted at P' and provided with a spring-arm, P'', which engages with the swinging frame J. To the lat-

ter is secured a spring-catch, Q, the free bent end of which engages a hook, O⁵, formed on the plate O². A pin, O⁶, projects from the upper end of the plate O², and is adapted to 5 engage with an arm, J³, secured to the swinging frame J at its pivoting on the said stud J'. The motion of the swinging frame J is limited by the stop-pin R, projecting from the plate J² into a notch, J¹.

10 The lever S is pivoted to a stud, S', secured to the swinging frame J, projects through a slot in the partition C', and has its bearing in the plate S², attached to the said partition C'. The outer spring end of the lever S is out of 15 contact with the wind-wheel A when the clock is to be wound up, and is in contact with the wind-wheel A, and prevents the turning of the same after the clock is wound up.

The operation is as follows: When the wind- 20 wheel A is caused to rotate by the air passing up through the flue C², the several parts of my improvement are in the position shown in Figs. 1, 2, and 3—that is, the swinging frame J is so placed that its pinion I¹ meshes into the 25 gear-wheel K of the train of gear-wheels which rotates the gear-wheel K and the pinion I¹, deriving its own rotary motion from the wind-wheel A, which imparts a rotary motion to the spindle I by the crank-arm H, and the 30 spindle transmits its rotary motion to the said pinion I¹, by means of the pinion I¹, meshing into the gear-wheel I², mounted on the same shaft I³ with the pinion I¹. The train of gear-wheels K imparts a rotary motion to the gear- 35 wheel L in the direction of the arrow a' (see Fig. 3,) and the mainspring, being attached by one end to the barrel E and by the other end to the spindle F, carrying the wheel L, is wound up, the barrel E remaining nearly sta- 40 tionary, only driving the clock mechanism, which is not interfered with as long as the winding up lasts. The gear-wheel L also turns the gear-wheel M on the spindle M', but does not turn the gear-wheel M², which operates the 45 striking mechanism as the pawl M³ glides over the ratchet-wheel M⁴, (which is also turned by the rotation of the spindle M',) and consequently does not move the gear-wheel M² as long as the winding up lasts.

50 For every revolution of the gear-wheel L the pin E', attached to the spring-barrel E, turns the segmental gear-wheel N² the distance of one tooth, and consequently turns the cam N' the same distance, so that the collar O, resting 55 on the cam N', is forced sidewise by the same, and when the mainspring is entirely wound up in the barrel E the collar O is in its uppermost position on the cam N' and forces the free end of the spring O' outward, which releases 60 the spring Q, attached to the swinging frame J, from the notch O⁵, and the lever P is moved in the direction of the arrow b' by the inclined slot O³, so that the spring P² throws the swinging frame J into the position shown in Fig. 4, 65 whereby the swinging frame J disengages the pinion I¹ from the gear-wheel K of the train of gear-wheels connected with the gear-wheel

L. The arm J³ then rests on the lug O⁶, and prevents the voluntary return of the swinging frame J. This sudden movement of the swinging frame J forces the arm S to move in the direction of the arrow c', the plate S² being fulcrumed, so that the spring end of the arm S engages with the wind-wheel A and prevents its further rotation. The mainspring, 70 attached to the barrel E and the spindle F, causes the latter to rotate in the inverse direction of the arrow a', as soon as the said spring is wound up, as above stated, and the wheel L is then also rotated in the same direction with the spindle F, and thereby reverses the motion of the segmental gear-wheel N² and the cam N', so that the collar O and the free end O² of the spring O' are gradually drawn inward until the cam is in its innermost position when the mainspring is nearly unwound. 75 Then the lug O⁶, moving inward with the free end of the spring O', releases the arm J³ and the inclined slot O³, and the free end O² of the spring O' forces the lever P back to its former 80 position, so that the spring arm P² throws the swinging frame J to its former position, (shown in Fig. 3,) whereby the lever S disengages the wind-wheel A, and thereby the latter is free to rotate, and the pinion I¹ again meshes into the 85 gear-wheel K of the train of gear-wheels which imparts motion to the gear-wheel L and the spindle F in the direction of the arrow a', and the winding of the mainspring again commences, as above described. The spring Q engages with the notch O⁵, and holds the swinging frame J in a locked position. 90 When the mainspring is unwound, the wheel L operates on the gear-wheel M² by means of the gear-wheel M, turning the spindle M', which rotates the ratchet-wheel M⁴, and as the pawl M³ is now in active engagement it turns the ratchet-wheel M⁴, to which the pawl M³ is pivoted, and first compresses the spring M² to its 95 limit, and then turns the gear-wheel M², which 100 operates the striking mechanism. 105

It will be seen that when the motion of the gear-wheel L is reversed, so as to wind up the mainspring, the compressed spring M² keeps the gear-wheel M² in motion until the mainspring in the barrel E is wound up again, as the pawl M³ holds the ratchet-wheel M⁴ in position, so as to permit the spring M² to act on the gear-wheel M² and, consequently, on the striking mechanism, which is not interfered 115 with whether the mainspring is wound up or unwound.

The movement of the swinging frame J may be utilized in many ways to lock or unlock the wind-wheel A—as, for instance, a double 120 door attached to the frame B could be opened or closed by the movement of the swinging frame J, which opening and closing of the door would cause a stopping or running of the wind-wheel.

Having thus fully described my invention, I claim as new and desire to secure by Letters Patent—

1. The combination of a clock actuated by

a spring, a swinging frame operated by the said spring, and a lever pivoted to the said swinging frame with a wind-wheel which can be locked by the said lever, substantially as 5 set forth.

2. The combination of a clock actuated by a spring, a locking device operated by the said spring, a swinging frame actuated by the said locking device, and a lever pivoted to the 10 said swinging frame with a wind-wheel which can be locked by the said lever, substantially as described.

3. The combination of a clock mechanism actuated by a spring, a spindle also operated 15 by the said spring, and a locking device connected with the spindle, with a swinging frame operated by the locking device of the spindle, a lever pivoted to the swinging frame, and a wind-wheel which can be locked by the said 20 lever, substantially as shown and described.

4. In a clock-winding mechanism, the barrel E, operating the clock mechanism, and the pin E', attached to the said barrel E, in combination with the spindle F, connected with 25 the barrel E by the mainspring F', the gear-wheel L, attached to the said spindle F, and the segmental gear-wheel N², mounted on the gear-wheel L, substantially as shown and described.

30 5. In a clock-winding mechanism, the barrel E and the pin E', in combination with the spindle F, the gear-wheel L, attached to the same, the segmental gear-wheel N², and the cam N', operating on the loose collar O, substantially as shown and described.

35 6. In a clock-winding mechanism, the cam N', and the collar O, operated by the same, in combination with the spring O', having an inclined slot, O³, and the lever P, actuating the 40 swinging frame J, substantially as shown and described.

7. In a clock-winding mechanism, the cam N', the collar O, operated by the cam N', and the spring O', having an inclined slot O³, in combination with the lever P, the spring-arm P², 45 attached to the lever P, and the swinging frame J, substantially as shown and described.

8. In a clock-winding mechanism, the cam N', the collar O, operated by the cam N', and the spring O', provided with the bent end O², 50 having an inclined slot, O³, and a hook, O⁵, in combination with the lever P, the swinging arm P², the swinging frame J, and the spring Q, attached to the swinging frame J, substantially as shown and described.

55 9. In a clock-winding mechanism, the cam N', the collar O, operated by the cam N', and the spring O', provided with the bent plate O², having an inclined slot, O³, a hook, O⁵, and a 60 lug, O⁶, in combination with the lever P, the spring-arm P², the swinging frame J, provided

with the spring Q and the arm J³, substantially as shown and described.

10. In a clock-winding mechanism, the swinging frame J, and a device for operating 65 the same from the spindle F, in combination with the arm S, pivoted on the swinging frame J, and having its fulcrum on the plate S', substantially as shown and described.

11. In a clock-winding mechanism, the 70 swinging frame J, operated from the spindle F, and the arm H, connected with a train of gear-wheels mounted in the swinging frame, in combination with the wind-wheel A, mounted on the spindle A', provided with the 75 crank-arm G, substantially as shown and described.

12. In a clock-winding mechanism, the swinging frame J, and the arm H, receiving a 80 rotary motion from the wind-wheel and operating a train of gear-wheels mounted in the swinging frame, in combination with a train of gear-wheels, K, connecting the train of gear-wheels mounted in the swinging frame J with the gear-wheel L, mounted on the spindle F, 85 substantially as shown and described.

13. In a clock-winding mechanism, the wind-wheel A, mounted on the shaft A', provided 90 with a crank-arm, G, the arm H, attached to a spindle, I, operating a train of gear-wheels, and the swinging frame J, in combination with the train of gear-wheels K, the gear-wheel L, the spindle F, and a device for operating the 95 swinging frame J from the spindle F, substantially as shown and described.

14. In a clock-winding mechanism, the wind-wheel A, mounted on the shaft A', provided 100 with a crank-arm, G, the arm H, attached to the spindle I, operating a train of gear-wheels, and the swinging frame J, carrying the said 100 train of gear-wheels, in combination with the train of gear-wheels K, the gear-wheel L, the shaft F, the mainspring F', and the barrel E, operating the clock mechanism, substantially as shown and described. 105

15. In a clock-winding mechanism, the gear-wheel L, the gear-wheel M, meshing into the same, the spindle M', carrying the gear-wheel M, and the ratchet-wheel M⁶, secured to the said shaft or spindle M', in combination with 110 the ratchet-pawl M¹, engaging the ratchet-wheel M⁶, the ratchet-wheel M⁴, mounted loosely on the shaft M' and carrying the pawl M¹, the spring-pawl M⁵, engaging the ratchet-wheel M⁴, the spring M³, and the gear-wheel 115 M², operating the striking mechanism of the clock, substantially as shown and described.

ABE ROBINSON.
